UNITED STATES PATENT OFFICE

112,823

DESIGN FOR AN OUTSIDE DOOR HANDLE

George E. Cossin, Detroit, Mich.

Application December 9, 1937, Serial No. 73,490

Term of patent 3½ years

To all whom it may concern:

Be it known that I, George E. Cossin, a citizen of the United States and a resident of Detroit, Michigan, have invented a new, original, and ornamental Design for an Outside Door Handle, of which the following is a specification, reference being had therein to the accompanying drawing forming part thereof.

Fig. 1 is a top plan view of the outside door handle showing my new design.

Fig. 2 is a side elevation of the same.

Fig. 3 is a sectional view taken on the line 3—3 of Fig. 2.

Fig. 4 is a sectional view taken on the line 4—4 of Fig. 2 while

Fig. 5 is a sectional view taken on the line 5—5 of Fig. 2.

The drawing is shaded to show contrasting appearance between the handle, the shank and the circular inset on the top of said handle.

What I claim is:

The ornamental design for an outside door handle, as shown and described.

GEORGE E. COSSIN.
